ELECTRICALLY OPERATED MUSICAL DEVICE

John F. Leonardson, Milwaukee, Wis.

Application October 3, 1947, Serial No. 777,666

6 Claims. (Cl. 84—405)

1

This invention relates to a musical instrument preferably in the form of a toy designed and intended for use by children.

The device is simple and inexpensive in construction and operation, the latter being electrical as hereinafter described.

In the latter arrangement, I employ a series of electromagnets in the form of solenoids associated with xylophone bars which when struck or impacted by the armatures of the solenoids produce sounds or tones as controlled by a playing card or pattern used with the device.

The card has a series of contacts in electrical circuits with the electro-magnets so the selection displayed on the card may be easily and readily played by touching a selector, also in the circuit, with contacts on the face of the card to complete the circuits to energize the magnets to sound the bars.

A further object of my invention is to have the contacts on the card substantially flush or otherwise arranged on the card so that the selector may be easily and quickly moved over the card from one contact to the other without interruption by any barriers on the card. This facilitates rapid, easy and smooth playing of the selection on the card by "words," the latter being printed on the face of card adjacent the contacts.

A further object of my invention is to provide the card with a wiring circuit connecting the contacts on the card with elements on the card to make electrical contact with yieldable contacts on the device on placing the card in playing position on the cabinet or support of the device.

The invention consists further in the structural features and the combinations thereof hereinafter described and claimed.

In its broadest aspect, my invention includes the combination of electrically operated devices, a support having separate contacts thereon, one for each of said devices and connected in electrical circuit therewith, a card member having electrical contacts and engageable with the contacts on the support on placing the card in operative or playing position thereon, additional contacts on the card in circuits with first named card contacts, and a selector or equivalent means for completing the circuits on touching the last named card contacts for operating said devices.

In accompanying drawings—

Fig. 1 is a top plan view of a toy musical instrument constructed in accordance with my invention;

Fig. 2 is a front view of the device;

Fig. 3 is a longitudinal sectional view taken on line 3—3 of Fig. 1;

Figs. 4 and 5 are similar sectional views taken on lines 4—4 and 5—5, respectively, of Fig. 3;

2

Fig. 6 is a transverse sectional view taken on line 6—6 of Fig. 3;

Fig. 7 is an under side view of one layer of a playing card or pattern element used with the device to show the electrical wiring diagram embodied in the card;

Fig. 8 is a top plan view of a card or pattern element showing a modification to be hereinafter described;

10 Fig. 9 is a view of a wiring diagram used in the device;

Fig. 10 is a sectional view taken on line 10—10 of Fig. 7;

Fig. 11 shows the musical notation of the selection on the card shown in Figs. 1 and 7; and

Fig. 12 is a view showing a card wiring arrangement for sounding the notes by octaves.

In the drawings, 1 indicates the outer cabinet or housing of the device generally rectangular in shape and of a size to be readily and easily lifted and carried from place to place as a toy musical instrument by children for whom the device is particularly designed and intended.

The cabinet 1 is preferably made of wood, wood veneer or other desired relatively light material as plastic of the appropriate color or color combinations and hollow to have, horizontal, top and bottom walls 2, 3, and upright end walls 4, 5, and front and rear walls 6, 7, respectively, as shown in Figs. 1 to 6, inclusive. The walls are secured together to impart rigidity and strength for the cabinet and to support within the same the respective parts, next being described, to provide a toy musical device and the electrical means for operating it.

Specially, the musical instrument illustrated is of the xylophone type having a complement of metal tone bars 8, 8 supported within the cabinet 1 just below the top wall 2 on lateral rails 9, 9 and of the desired tone range. In the instance shown, the bars 8 are in the key of "C" and comprise on octave from middle "C" to "G" next above as shown in Figs. 4 and 8. The bars 8 are horizontally disposed and are loosely mounted on the rails 9 by headed pins 10 as shown in Figs. 3 and 6. The pins 10 pass through slightly enlarged apertures 11 in the bars and the latter rest on felt or cushion pads or strips 12 as depicted in Fig. 6. The end supports 13 for the rails 9 are secured to the inside of the walls 4, 5 of the cabinet 1 as herein shown.

Arranged in the cabinet 1 below the xylophone bars 8 for striking or impacting the same for sounding them is a complement of electro-magnets of the solenoid type 14, one for each bar 8. The solenoids 14 are vertically disposed below the bars 8 in a supporting structure 15 having a base rail 16, secured to the bottom wall 3 of the cabinet with spacers 17 therebetween,

The tube element 18 of each solenoid 14 provides a guide for the core or armature 19 of the solenoid 14 and a mounting for its coil 20 as detailed in Fig. 6. The parts are so arranged and proportioned that the armatures 19 are selectively projected upwardly to strike the associated bars 8 with sufficient force to sound them.

On the bottom wall 3 below the solenoid tubes 18 is a cushion means 21 to dampen the downward stroke of the armatures 19 by gravity when the associated solenoids 14 are de-energized as when playing the device. The opposite ends of the tubes 18 are open and the solenoids 14 are in the electrical circuit of the device to be presently described.

The upper surface of the top wall 2 is horizontally flat or substantially so, or it may be at a slight upward inclination to support a playing card or pattern 22 used with the device when playing a song or musical selection within the compass of the tone range of the xylophone bars 8. This card 22 is placed on the top wall 2 of the cabinet 1 between and against the upwardly extending relatively short stops or abutments 23 adjacent the front wall 6 of the cabinet and the electrical contacts 24, 24 of the yieldable or spring type secured to the rear wall 7 of the cabinet 1 by a series of fasteners and binding pins, the latter being marked 25 and insulated from the wall 1, one pin 25 for each contact 24 as detailed in Fig. 6.

The contacts 24 are shielded by a guard housing 26 secured to the rear wall 7 of the cabinet 1 and projecting to the desired extent above the top wall 2. The wall portion 27 of the shield 26 overhangs and protects the contacts 24 as shown in Fig. 6.

On the rear edge of the card 22 are mounted contacts 28, 28 which for inexpensiveness of construction, are preferably in the form of metal clips clamped over the edge of the card 22 in spaced relation along the length of the latter. In Fig. 8 the card 22 is shown as having as many contacts 30 as there are xylophone bars 8 used in the device. Or as shown in Fig. 7 there may be on the card only the number of contacts 28 as required for the tone range encompassed by the selection on the card; namely, eight as shown in Figs. 7 and 11.

The clip contacts 28 and 30 are on the edge of the cards opposed to the cabinet contacts 24 to engage the same on placing the card in its playing or usable position on the top wall 2 of the cabinet as shown in Figs. 1 and 6.

Regardless of the particular number of contacts 28 used on a card 22, the contacts 28 are in the electrical wiring circuit employed in the card. For example, the card 22 on the cabinet 1 in Fig. 1 has the selection "Happy Birthday to You" printed in word symbols in several horizontal rows on the upper or front face of the card. On the card are a complement of electrical metal contacts 31, 31 arranged in spaced relation in the several rows in which the song is displayed, one contact 31 under or adjacent to each word symbol as shown in Fig. 1. Hence, the selection on the card 22 is played by "word" and not by note. In this manner of playing the selection the knowledge of notes is not needed and with wording appearing the player and those with him can sing the selection from the words.

Each contact 31 is of the headed type having a head portion 32 and a stem or similar portion 33. The latter extends into the card for connection with the electrical wiring, while the head

portion 32 overlays the outer surface of the card with its marginal edges substantially flush with the upper surface of the card as shown in Fig. 10. The purpose of this arrangement will be presently described.

As shown in Figs. 6 and 10, the card 22 is of double layer construction with the wiring between the two layers 34, 35 as detailed in Fig. 10. This wiring is arranged to connect all the contacts 31 for sounding the tones for the selection depicted on the card. For example, in the selection depicted on the card 22, the selection is written in the key of "C" with a tone range for the octave "G" to "G" immediately above middle "C." Perhaps to better illustrate the arrangement attention is directed to Figs. 7 and 11.

The clips 28 on the card 22 are connected by wiring in the card to all of the card contacts 31 for the corresponding tones. For example, clip 28, the first to the left for low tone "G" is connected by wiring 36 and 37 to all low "G" card contacts 31. The next clip 28 for "A" is connected by the wiring 38 with all "A" tone contacts 31 on the card. The clip 28 for "B" is connected by wiring 39 to all "B" card contacts 31. Wiring 40 in the card connects clip 28 for "C" with all "C" card contacts 31 and wiring 41, 42, 43 and 44 connect "D" to "G" clips 28 inclusive with corresponding card contacts 31.

The musical notation for the selection described is shown in Fig. 11 and the notes on the staff are indicated by their letters. These same letters are duplicated on the card contacts 31 in Fig. 7. Hence, the comparison with these two figures is manifest.

In the modification shown in Fig. 8, the card 29 has a full complement of contacts 45 representing the xylophone bars 8 mounted in the cabinet 1, each contact 45 being wired to one contact 30. With the arrangement shown in Fig. 8 harmony can be produced by using a pair of selector members to be presently described.

For playing the selection on a card, I provide a selector 46 in the form of a rod or pencil having a ball point 47 as shown in Fig. 9. Here the electrical circuit is shown as comprising leads 48, 49 from the solenoid coil 20, the lead 48 being connected by a wire 50 with a contact 24, the lead 49 is connected by a wire 51 with one terminal of the secondary 52 of the transformer 53, the primary 54 of the transformer being connected to with a plug 55 which is inserted in a wall fixture of a suitable source of current supply. The selector 46 is connected by a wire 56 with the secondary 52 of the transformer 53.

The electrical circuit includes a binding post 57 in the front wall 6 of the cabinet 1 and to which post 57 the selector wire 56 is connected as shown in Figs. 1, 2 and 6. The point of the selector 46 in Figs. 1 and 2 is shown of the tapered character, rather than the ball shape as depicted in Fig. 9. Each solenoid 14 is connected to the transformer 53 and all solenoids are controlled by the one selector 46.

The contact elements 31 on the card are indicated in Fig. 9 and when touched by the selector point 46a completes the circuit of the solenoids 14 to energize them and sound the tones of the bars 8 struck by the armatures 19. All the magnets are connected in the electrical circuit as above described and the solenoids 14 are individually energized as the selector 46 is moved over the card to touch the contacts 31 thereon. Touching the contacts 31 in regular order sounds the selection on the card.

The contact heads 32 being substantially flush with the surface of the card and being crowned or rounded in shape as shown in Fig. 10, the selector point 46a or 47 can be moved quickly and easily without interruption from one card contact to the next. Thus, the selection of the card may be played smoothly or with the time intervals desired therebetween by the operator. The selector point 46a is merely slid over the card from one contact to the other and when the contacts 31 are touched the magnets are energized to sound the bars 8 controlled thereby.

A pair of selectors 58, 58 are in the circuit with the magnets and the playing bars for the card 29. This enables two notes or tones to be played at a time and the desired harmony produced. For example, two contacts 45 on the card 29 are touched by the selectors 58 in the hand or hands of the operator.

As a further modification of my invention each contact 59 on the edge of the card 60 as shown in Fig. 12, controls not only its own tone but an octave thereof. This provides a more solid tone. This arrangement comprises wiring 61 from contact 59 and wiring 62 to octave contact 59a.

The cabinet 1 has additional guides 63, 63 to the sides of the card as shown in Figs. 1 to 3.

The device shown and described is believed to be novel and enables the operator to play the device at the speed and with skill desired.

The front wall 6 of the cabinet 1 may provide with a sound opening 64 covered by a screen mesh 65 to protect the parts located in the cabinet from contact through said opening.

The details of construction and arrangement of parts shown and described may be variously changed and modified without departing from the spirit and scope of my invention, except as pointed out in the annexed claims.

I claim as my invention:

1. The combination of a series of electrically operated devices, a support having a series of contacts each electrically connected with one of said devices, a replaceable control card having a series of contacts each engageable with certain of said support contacts upon application of said card to said support, said control card having a second series of contacts arranged in predetermined sequence and each electrically connected to one of said first named card contacts, and a circuit closing selector movable into successive contact with the card contacts of said second series to effect operation of said devices in a sequence predetermined by the sequential arrangement of said last named contacts on said replaceable control card.

2. The combination of a series of electrically operated devices, a support having a series of contacts each electrically connected to one of said devices, a replaceable control card applicable to said support and having a series of contacts thereon, means for positioning said card on said support to effect contact of each of said card contacts with certain of said support contacts, said control card having a second series of contacts arranged in predetermined sequence and each electrically connected to one of said first named card contacts, and a circuit closing selector movable into successive contact with the card contacts of said second series to thereby effect operation of said devices in a sequence determined by the sequential arrangement of said last named contacts on said replaceable control card.

3. The combination of a series of electrically

operated devices for producing tones of different pitch, a support having a series of contacts each electrically connected to one of said devices, a control card replaceably applicable to said support and having a series of contacts respectively engageable with said support contacts upon application of the card to said support, said control card having a second series of contacts arranged in predetermined sequence and each electrically connected to one of said first named card contacts, and a circuit closing selector movable into successive contact with the card contacts of said second series to thereby effect operation of said devices in a sequence predetermined by the sequential arrangement of said last named card contacts and thus produce the notes of a tune as prescribed by said control card.

4. The combination of a series of electrically operated devices for producing tones of different pitch, a support, a replaceable control card adapted for application to said support, said card having the words of a song thereon, said card also having thereon a series of contacts in the same order of arrangement as said words, means rendered effective by application of the card to said support for electrically connecting each of said contacts to certain of said devices, and a circuit closing selector movable into successive contact with said contacts to effect operation of said devices in predetermined order and thereby sound the notes of said song in the same order as the words of the song appearing on said control card.

5. The combination of a series of electrically operated devices, a support having a series of concealed contacts each electrically connected with one of said devices, a replaceable control card for application to said support, said card having a series of contacts for respective contact with said support contacts upon application of said card to said support, said card also having a series of exposed contacts each electrically connected to certain of said first named card contacts, and a circuit closing selector manually operable into successive contact with said exposed contacts to effect operation of said devices in the order of arrangement of said exposed contacts.

6. The combination of a series of electrically operated devices, a support, a replaceable control card for application to said support, a series of electrical contacts carried by said card, means rendered effective by application of said card to said support for electrically connecting each of said contacts to certain of said devices, said means including electrical connections carried by said card, and a circuit closing selector movable into successive contact with said contacts to effect operation of said devices in a sequence dependent upon the arrangement of said contacts.

JOHN F. LEONARDSON.
